His Attorney.

UNITED STATES PATENT OFFICE

JOHANNES SCHMIDT, OF BERLIN-FRIEDENAU, GERMANY, ASSIGNOR TO GENERAL ELECTRIC COMPANY, A CORPORATION OF NEW YORK

ELASTIC-FLUID TURBINE AND VALVE STRUCTURE FOR USE THEREWITH

Application filed September 25, 1929, Serial No. 395,175, and in Germany October 4, 1928.

The present invention relates to elastic fluid turbines and valve structures for use therewith, and especially to installations wherein a driven machine is connected to an elastic fluid turbine and an electric motor, the machine being driven normally by the electric motor and being driven by the turbine only in case the motor fails. Such installations are termed usually three-unit sets. 5 In connection with such sets, it is known to provide in the elastic fluid admission conduit for the turbine a quick opening valve, which is normally held closed, and which is opened in case the speed of the set falls below a predetermined low value, and a separate quick 10 closing valve which is normally held open, and which is closed in case the speed of the turbine exceeds a predetermined high value. The object of the present invention is to provide an improved construction and arrangement wherein a single valve performs the function of both a quick opening and quick closing valve. 15 For a consideration of which I believe 20 to be novel in my invention, attention is directed to the following specification and the claims appended thereto.

In the drawing, Fig. 1 is a diagrammatic view partly in section of a three-unit set 25 equipped with a valve structure embodying the invention, and Fig. 2 is a vertical sectional view of the operating part of the valve structure.

Referring to the drawing, 1 indicates an elastic fluid turbine having an admission conduit 2 and an exhaust conduit 3, and 4 indicates an electric motor which receives electrical energy from any suitable source. Turbine 1 and motor 4 are both connected 30 to a driven machine 5, here indicated as being a centrifugal pump. In conduit 2 is a regulating valve 6 actuated by a speed governor 7 through the intermediary of a fluid actuated motor 8, the arrangement including the usual pilot valve and follow-up connections. The construction and operation of an arrangement of this type is well understood and requires no detailed description. With the arrangement shown, when the speed 45 of the turbine decreases, the speed governor

lifts governor lever 9 to effect an opening movement of valve means 6, while when the speed of the turbine increases the speed governor moves governor lever 9 downward to effect a closing movement of valve 6. Normally the machine 5 is driven by electric motor 4, governor 7 being so set that at the normal operating speed for motor 4, valve 6 is held closed. When the speed drops below a predetermined low value, due, for example, to failure of motor 4, speed governor 7 effects the opening of valve 6 to admit elastic fluid to the turbine, whereby the turbine takes up the load. 55

According to my invention, I provide in connection with a set of foregoing type, a valve 10 which is located in conduit 2, and which performs the function of both a quick opening valve and a quick closing valve. Normally, valve 10 is held closed by a catch, 60 which catch is released when the speed of the set decreases below a predetermined low value to permit the valve to open, and in connection therewith means are provided whereby, in case the speed of the turbine exceeds a predetermined high value, valve 10 is closed. 65

Referring particularly to Fig. 2, 11 indicates the stem of valve 10 and 12 indicates a casing which contains the operating mechanism for the valve. The upper end of stem 11 is connected rigidly to a piston 13, which slides in casing 12 and is held from turning by a key 14, which projects into a vertical groove 15 in the wall of piston 13. Beneath piston 13 is a spring 16, which is under compression and acts in a direction tending to force piston 13 upward. In the side of piston 13 is a notch with which engages a catch 17, pivotally mounted in the side of casing 12. 70 Connected to the outer end of catch 17 is an arm 18 (see Fig. 1) which is connected by a link 19 and a bell crank lever 20 to a rod 21, the lower end of which lies in the path of movement of a finger 22 connected to the stem of speed governor 7. 23 is a spring which acts in a direction to normally hold catch 17 in engagement with the notch in piston 13. 75 With the above described arrangement, when the speed of turbine 1 decreases below 80

a predetermined low value, the stem of speed governor 7 moves upward sufficiently to bring finger 22 into engagement of lower end of rod 21, thereby raising the rod and turning catch 17 to a position wherein piston 13 is released. When piston 13 is released, spring 16 moves it upward to quickly open valve 10. Valve 10 thus acts as a quick opening valve which is operated in case the speed of the turbine decreases below a predetermined low value.

Connected to and forming in substance a continuation of stem 11 is a stem extension 24, which is connected to the upper end of stem 11 and to piston 13 by a thrust bearing 25 which permits stem extension 24 to be turned relatively to stem 11 and piston 13. Stem extension 24 is threaded as is indicated at 25^a, and on threads 25^a is an elongated nut 26, provided on one side with key 27, which slides in a groove 28 on the inner surface of a sleeve 29 which surrounds stem extension 24 and forms a part of a piston 30. Nut 26 is adapted to travel on stem extension 24 between a collar 31, fixed on stem extension 24 and an inturned flange 32 on the upper end of sleeve 29. Located between a head 33 fixed on the upper end of casing 12 and piston 30, is a spring 34 which acts in a direction tending to force piston 30 downward in casing 12. Piston 30 is held normally against movement by a catch 35, which engages in a notch in the side of piston 30. Catch 35 is pivoted in the side of casing 12 and at one end is connected by an arm 36 (see Fig. 1) to a link 37, which in turn is connected by a bell crank lever 38 to the upper end of a trip rod 39. The lower end of trip rod 39 stands in a position to be engaged by the plunger of an emergency governor 40 arranged on the turbine shaft. 41 is a spring which acts in a direction to hold catch 35 in engagement with the notch in piston 30. Piston 30 is held from turning by a key 42, which engages in vertical slot 43 in its side wall. Connected to the upper end of valve stem extension 24 is a hand wheel 44, by means of which stem extension 24 may be turned. Normally piston 30 is held in the position shown in Fig. 2 by catch 35. In case the speed of the turbine exceeds the predetermined high value, the plunger of emergency governor 40 will fly out due to a centrifugal force and strike the lower end of rod 39, thereby raising the rod and turning catch 35 to release piston 30, whereupon spring 34 will force the piston downward. If at this time valve 10 is opened it will be forced shut, spring 34 being stronger than spring 16.

During normal operation, the parts occupy the positions shown in drawing, valve 10 being held closed. If the speed of the turbine decreases below a predetermined low value, catch 17 will be turned to release piston 13, as already explained, and spring 16 will force

piston 13 upward, bringing it into engagement with the lower surface of piston 30, which forms a stop to limit its upward movement. Also the space between the two pistons functions as a dash-pot to cushion the movement of the piston. When piston 13 moves upwardly, it carries with it stem extension 24, and nut 26, the upper end of nut 26 coming closer to inturned flange 32. The surrounding flange of hand wheel 44 slides on the upper end of casing 12. To close valve 10 again, hand wheel 44 is turned in a direction to cause nut 26 to travel up stem 24, and after the nut strikes flange 32 continued turning of the hand wheel in the same direction will force stem extension 24, stem 11 and piston 13 downward until the valve is again seated, catch 17 engaging its notch in the piston. Hand wheel 44 is then turned the other direction to run nut 26 down the stem extension 24 to its normal position.

If, while valve 10 is open, catch 35 is moved from engagement with the notch in piston 30, whereby the piston is released, the piston will be moved downward by spring 34, forcing valve 10 to closed position. As stated above, spring 34 is stronger than spring 16. To reset the mechanism, hand wheel 44 is turned in a direction to cause nut 26 to travel upward on stem extension 24, whereby the upper end of the nut engages flange 32 and forces piston 30 upward against the action of spring 34 until catch 35 engages in the notch in piston 30. Hand wheel 44 is then turned in the opposite direction to bring nut 26 back to the position shown in Fig. 2.

While I have described the invention especially in connection with a three-unit set, it is to be understood that the invention is not limited thereto necessarily, but may be utilized wherever it may be found to be applicable.

What I claim as new and desire to secure by Letters Patent of the United States is:

1. The combination with an elastic fluid turbine, of a valve controlling flow of elastic fluid to the turbine, means which effects the opening of said valve when the speed of the turbine decreases below a certain low value, and means which effects the quick closing of said valve when the speed of the turbine exceeds a predetermined high value.

2. The combination with an elastic fluid turbine having a regulating speed governor and an emergency speed governor, of a valve controlling flow of elastic fluid to the turbine, means actuated by the regulating speed governor to effect opening of said valve when the speed of the turbine decreases below a certain low value, and means controlled by the emergency speed governor which effects closing of said valve when the speed exceeds a certain high value.

3. A valve structure comprising a seat, a valve adapted to engage the seat, a stem for

the valve, a piston to which the stem is connected, a spring which moves the piston in a direction to open the valve, a catch for holding the valve closed against the action of said spring, a stem extension pivotally connected to the end of said stem, a nut threaded onto said stem extension, a second piston located above the first piston, a spring which tends to force said piston in a direction to close the valve, a catch for holding said second piston against the action of such spring, a flange carried by the second piston and adapted to be engaged by said nut, whereby the second piston may be moved by said nut traveling along the stem, and means for releasing said catches.

4. A valve structure comprising a seat, a valve adapted to engage the seat, a stem for the valve, a piston to which the stem is connected, a spring which moves the piston in a direction to open the valve, a catch for holding the valve closed against the action of said spring, a stem extension pivotally connected to the end of said stem, a second piston located above the first piston, a spring which tends to force said second piston in a direction to close the valve, a catch for holding said second piston against the action of such spring, means for releasing said catches, and means actuated by the stem extension for resetting said pistons.

In witness whereof, I have hereunto set my hand this 12th day of September, 1929.

JOHANNES SCHMIDT.
